UNITED STATES PATENT OFFICE.

HERMAN NOWAK, OF BRIDGEPORT, INDIANA.

MACHINE FOR SHAPING METAL TROUGHS AND TUBES.

1,187,374.

Specification of Letters Patent. Patented June 13, 1916.

Application filed May 14, 1915. Serial No. 27,995.

To all whom it may concern:

Be it known that I, HERMAN NOWAK, a citizen of the United States, residing at Bridgeport, in the county of Marion and 5 State of Indiana, have invented certain new and useful Improvements in Machines for Shaping Metal Troughs and Tubes, of which the following is a specification.

My invention relates to machines for bending and shaping sheet metal material so as 10 to particularly form tubing or pipes or eavestroughs or gutters.

Among the objects of the invention, I aim to provide a die means to roll the material 15 fed through the machine may coöperate with suitable dies or shapers to impart the general final conformation to the material together with suitable roller means to provide finishing or connecting beads, flanges, or the like; 20 to provide a die means to roll the material into tubular form having lock flanges together with a mandrel or arbor over which the tube passes after formation; to especially provide means to interlock the said flanges, 25 and means to expand the tubes after interlocking of said flanges prior to completion of the tube as a final product.

Also I aim to provide a machine having a tube forming die together with removable 30 supporting means, whereby the die may be removed and a gutter-forming die substituted.

With the foregoing as well as additional objects such as will hereinafter appear, in view, the invention resides in the novel details of construction, arrangement and combination of the parts as illustrated in the accompanying drawings of one preferred form.

In said drawings:—Figure 1 is a top or plan view of the machine; Fig. 2 is a side 40 elevation; Fig. 3 is a central longitudinal sectional view along the line 3—3 of Fig. 1; Fig. 4 is a cross sectional view on the line 4—4 of Fig. 1, with the supporting beams omitted but showing tubing in the process 45 of manufacture; Fig. 5 is a fragmentary side elevation of swaging means which may be employed; Fig. 6 is a detail perspective view of the pipe-forming die; Fig. 7 is a fragmentary detail illustrating corrugating 50 means which may be employed, and Fig. 8 is a perspective view of the die member and supporting means used in the manufacture of guttering.

Referring specifically to the drawings, the operating mechanism of the machine may be 55 mounted from a suitable base, for instance, longitudinal side beams 1. At the feed end of the machine, are mounted from the beams 1, side walls 2 which are spanned by and mount a suitable form of feed table 3. Also 60 in walls 2 are mounted as bearings, a power or drive shaft 4 and an auxiliary shaft 5 parallel therewith and also in the same vertical plane. On the shafts 4 and 5 are mounted suitable rollers 6. Adjacent the 65 rollers 6 are also mounted vertically alined shafts 7 and 8 in the walls 2. The shaft 8 has mounted thereon a concave shaping roller 9 while the shaft 7 has mounted thereon a convex shaping roller 10. Shaft 4 is 70 driven from any suitable source of power as by a belt (not shown) which may coöperate with a fixed pulley 11 and a loose pulley 12 both mounted on the shaft. Also a fly wheel 13 may be mounted on said shaft 4. In addition, shaft 4 has a gear wheel 14 keyed thereto which meshes with a gear wheel 15 keyed to shaft 5. Gear wheel 15 meshes with a gear wheel 16 which is an idler and mounted from a stub shaft 17 extending 75 from one side plate 2, and meshing with a gear wheel 18 keyed to shaft 8 and which in turn meshes with a gear wheel 19 fastened on shaft 7. Brackets 20 and 21 are secured 80 to the inner faces of plates 2, one on each of the opposite sides of the machine. Bracket 20 mounts two rollers 22 while bracket 21 mounts two rollers 23 and 24. The material which may be sheet metal is fed from table 3 between the rollers 6 and 85 then guided between the rollers 7 and 8 which results in convexing the material as will be seen by the dotted lines at 25 in Fig. 4 which represents the material. One longitudinal edge of this dished material passes 90 between the rollers 22 which results in the provision of a lock flange 26 at one side of the material as seen in Fig. 4. At the other longitudinal edge of the material, it passes between the rollers 23 and 24 to provide a 95 lock flange 27 as also seen in said Fig. 4. It will be noted that roller 23 is substantially conical in order that it may properly be disposed between the flange 27 and remainder 100 of the material in the process of manufacture. 105

Second side plates 28 are fastened to the beams 1 and a supporting bracket 29 spans the plates 28 and is removably fastened thereto as by set-screws 29'. Bracket 29 in its upper surface, has a concavity 30 in which is seated a die 31 of the form shown in Fig. 6 and which is fastened to the bracket by means of bolts 31'. This die is shaped so as to provide the slot 33 adjacent its frustum 10 end and angular edges 34 leading from the slot 33 to the base end of the die. Mounted at the top of the plates 28, is a bridge or cover plate 35 fastened in place by means of set-screws 36. Brackets 37 are fastened to 15 one end of the plate 35 by means of set-screws 38 which pass through elongated slots 39 of the brackets and which permit adjustment of the brackets relatively to the central longitudinal vertical plane of the machine. One bracket 37 mounts a roller 40 adjacent one end of the die 31, which roller 40 is frusto-conical and has its frustum uppermost. The other bracket 37 mounts a roller 41 substantially similar in shape to 20 the roller 40 but with its frustum lowermost. Roller 40 is preferably disposed in a lower plane than roller 41 and also out of transverse alignment therewith to better enable locking action on the part of flanges 26 and 27.

The material in dish form, provided with the lock flanges 26 and 27, after passing between the rollers 22, 23 and 24, passes into the die 31 and the flanges 26 and 27 overlap 25 the exterior of the die at edges 34. As the material advances, the interior shape of the die curls or rolls it substantially into the shape of a tube, but having the flanges 26 and 27 on the exterior of the die. At the 30 proper stage of advancement, flange 26 is engaged and guided by roller 40, while flange 27 is engaged and guided by roller 41 over the flange 26, whence it may interlockingly engage said flange 26. Suitable means 35 have been provided to expand the material at this stage which may be in the form of a substantially cylindrical arbor or mandrel 42, preferably provided with a tapered receiving end 43. This mandrel is supported 40 by grooved shaping rollers 44, 45 and 46. Said rollers 44, 45 and 46 also serve to draw the tubing over the mandrel. As said tubing passes over the tapered portion 43, same is expanded so that lock flanges 26 and 27 are 45 pulled into tight relation. Above the mandrel 42 is disposed a seaming roller 47 having a groove 48, see Fig. 1, which presses the flanges 26 and 27 into tight locked relation. As the tube passes between rollers 45 and 46, 50 the seam at the junction of the flanges is practically rolled out and the tube is practically a true cylinder. Roller 44 is preferably mounted on a shaft 49 journaled in standards 50 in which a shaft 51 is also journaled and on which the seaming roller 47 is

keyed. Beyond the seaming roller, on opposite sides thereof, guide plates for the material designated 52 are keyed. Rollers 45 and 46 may be mounted from shafts 53 journaled in standards 54.

In order to drive shaft 51 from shaft 4, sprocket gear wheels 4^a and 51^a are respectively mounted on these shafts and a sprocket chain 4^b trained over the sprocket wheels. Since a sprocket wheel 51^b is 70 mounted on shaft 51 and a similar wheel 53^a is mounted on upper shaft 53, and a sprocket chain 53^b passes over these wheels, shaft 53 is driven from shaft 51. Shaft 51 drives shaft 49 through the meshing of gear wheels 49^a and 49^b on these respective shafts, while upper shaft 53 drives lower shaft 53 as gear wheels 46^a and 46^b on the shafts 53, mesh.

After the cylindrical tubing has passed rollers 45 and 46, it may further pass 85 through a suitable swage or swedge, for instance, that of the type shown at A. This type, preferably, has a plurality of radiating arms 55 which bear directly against the tubing and which are pivoted as at 56 and 90 yield against the tension of springs as at 57. Such arms 55 enable the material to be readily removed from the machine, especially when made in a plurality of sections, since one section can be removed without 95 interference with another.

It may be desired to corrugate the tubing, in which event, I prefer to use the means shown in Fig. 7 and which is carried by a plate 58. This plate 58 has side ribs 59 which may removably slide into grooves 60 of plates 54. A ring 61 is positioned on plate 58 by means of brackets 62 and on this ring a suitable number of corrugating rollers 63 may be journaled so as to directly engage 105 the tubing which should pass through a central opening 64 of plate 58.

In some instances, it may be desired to form guttering with the machine, in which event, bracket 29 and die 31 are removed and the bracket 65 of Fig. 8 substituted and also mandrel 66 of Fig. 8 substituted for mandrel 43. Bracket 65 carries a die 67, the interior wall of which is tapered. The material is passed through this die 67 with 110 flanges overlapping its side edges and which are engaged for beading by rollers 68 journaled on arms 69 of the bracket 65.

Since merely the preferred embodiment of the invention has been illustrated and described, it is to be understood that changes in the details of construction may be resorted to within the spirit and scope of the appended claims.

I claim:—

1. In a machine of the class described, shaping means, means to form flanges on material shaped by the shaping means, a die through which the material passes, means to interlock flanges formed on the material, a 120

mandrel to be engaged by the material, and seaming means for the interlocked flanges coöperating with the mandrel.

2. In a machine of the class described, a die provided with a longitudinally disposed slot, means to pass material through the die; means to form the flanges on the material, a supporting structure for the die, rollers to interlock the flanges mounted on the supporting structure, and means operating to thereafter expand the material.

3. In a machine of the class described, a supporting structure, shaping rollers supported therefrom, flange forming rollers sup-

ported from said structure, a second supporting structure, a die carried by the second supporting structure, rollers to engage the flanges of material passing through the die to interlock the flanges mounted from the second supporting structure, and a mandrel coöperating with the die and last mentioned rollers.

In testimony whereof I affix my signature in presence of two witnesses.

HERMAN NOWAK.
